ATTORNEY

UNITED STATES PATENT OFFICE.

CHARLES D. SHEPARD, OF PEEKSKILL, NEW YORK.

DESIGN FOR A MATCH-SAFE.

SPECIFICATION forming part of Design No. 30,982, dated June 13, 1899.

Application filed May 11, 1899. Serial No. 716,447. Term of patent 3½ years.

To all whom it may concern:

Be it known that I, CHARLES D. SHEPARD, a citizen of the United States of America, and a resident of Peekskill, in the county of Westchester and State of New York, have invented a certain new and useful Design for a Match-Safe, of which the following is a specification.

Figure I is a front view of my match-safe. Fig. II is a vertical cross-sectional view taken through the center of Fig. I. Figs. III and IV represent details of the ornamentation on the safe.

The match-receptacles *ee* are integral with the front plate of the safe, a plate *f*, Fig. II, affording a backing for them.

The distinctive features of the match-safe are its outlines and plain ornamentation. The form of the border *b* along the edges of the plate is shown in enlarged cross-section by Fig. IV. The scalloped surface *a* is shown in

enlarged cross-section by Fig. III. At *c* is represented a hole for hanging the safe, with concave depressions about its upper portion. A raised surface is shown at *d* for the reception of a rivet or screw. A narrow convex 25 rib borders the upper edge of each of the match-receptacles. The lower point *g* has concave depressions, as shown. The surface above the top receptacle and the fronts of the receptacles are left plain for the reception of 30 any suitable words.

Having described my invention, what I claim as new, and desire to secure by Letters Patent, is—

The design for a match-safe as herein shown 35 and described.

CHAS. D. SHEPARD.
